GUN HAVING MEANS FOR DIRECTLY
CANTING THE TRUNNION AXISCarl Waninger, Dusseldorf, Germany, assignor to
Rheinmetall-Borsig Aktiengesellschaft, Dus-
seldorf, Germany, a corporation of GermanyApplication March 3, 1936, Serial No. 66,949
In Germany May 23, 1933

1 Claim. (Cl. 89—41)

The invention relates to gun mountings with mechanism for enabling the gun, without the carriage, to be so operated that it will still maintain its direction in space, when the platform on which the mounting is attached is subject to tilting. Such gun mountings have, between the usual trunnion axis and the vertical traversing axis on the base, a third generally horizontal axis extending parallel to the base. By suitable canting of the gun about this third axis the trunnion axis can be maintained always horizontal notwithstanding the tilting of the base or platform supporting the mounting, and by simultaneous turning of the gun about the trunnion axis, the gun maintains its direction in space unchanged. The aforesaid third or horizontal axis is herein designated as the horizon adjustment axis or shaft because it enables the effect of the shifting of the gun platform relatively to the horizon to be eliminated in the aiming of the gun. The horizon adjustment movements of the gun in traverse and elevation are effected by manual drive in accordance with horizon determining devices such as horizon telescopes, levels, or gyroscopes. Simultaneously the sighting devices may also be given horizon adjustment so that both elevation and also traversing corrections can be transmitted to them without re-calculation.

The invention provides for such gun mountings such an arrangement of the horizon adjustment parts that a simple and compact construction of the mounting is possible and the said adjustment can be performed in different independent ways. The arrangement is such that the means for imparting the horizon adjustment movements to the gun, acts at the intersection of the adjustment shaft with the axis of traverse.

As an example of means for imparting horizon adjustment movements to the gun there is herein described a double slide device arranged coaxial with the axis of the pivotal traverse motion of the gun and so equipped that it can be selectively locked to a part of the carriage participating in said motion, or to the fixed base. The device can also be disengaged from the horizon adjustment shaft.

If the double slide is engaged with the base, then the table or body of the slide is fixed relatively to the base, independently of turning of the gun and carriage. The operation of the slide can then be effected in known manner by a horizon gyroscope fixed to the platform at any suitable location.

If the double slide is engaged with the pivotable part of the carriage, then it can be operated in known manner by an inertia frame arranged under the carriage. If a control post is available, pivotable about three axes like the gun, then the double slide can be controlled from such post, also in known manner.

If the double slide is disengaged from the horizon adjustment shaft, then the latter can be turned by hand, according to the indications of a horizon determining device, for example a horizon telescope.

Summarizing, the gun mounting according to the invention makes it possible to obtain the following horizon adjustments:

- (1) Automatically under control by a horizon determining gyroscope fixed on the platform.
- (2) Automatically under control by an inertia frame turning with the gun carriage.
- (3) Automatically under control from a suitable triaxial control post.
- (4) Manually under control of a suitable horizon determining device.

By providing these various independent possibilities of horizon adjustment great reliability is guaranteed since upon failure of one of these means, adjustment of the gun for horizon can be effected by one of the other means.

The gun, adjusted for horizon, can be aimed in all four cases by normal traversing and elevating gears which are positively adjusted for horizon along with the gun.

An example of an embodiment of the invention is shown diagrammatically in the drawing.

About the base A fixed firmly to the ship there pivots a gun carriage member B, at the top of which and cutting the pivotal axis at right angles, there is mounted the horizon-adjustment shaft C. Around a fork C' formed on this shaft there is mounted a bifurcated cradle support D, pivotable about the trunnions E₃ of the gun cradle E₁ in which the gun barrel E is mounted. The cradle E₁ can be pivoted in the cradle support D by means of elevating gear, which includes a worm D₁ mounted in the cradle support D and a worm-toothed quadrant E₂ fixed to the cradle E₁.

The base A has an upwardly extending axial pillar M supporting a double slide device comprising a table F which can turn on the pillar and which has a guide F₂ extending parallel to the shaft C, for a longitudinal slide F₃. The slide F₃ has a transverse guide F₄ for a cross slide F₅, the movements of the slides F₃ and F₅ thus being at right angles to each other. A ball joint member G₂ lodges in a spherical cavity in the centre of the slide F₅. The centre of the ball joint member G₂ lies in the axis of the pillar M, that is the axis of pivoting of the carriage member B for the traverse of the gun, when the deck of the ship is horizontal. The member G₂ has a vertical axial bore in which engages a pin G₃ on the end of a forked lever G. The pin G₃ can move axially in the bore of the member G₂. The movements of the slides F₃, F₅ on the table F are effected in known manner through gearing by means of electric motors, which are controlled, in manner 60

known to those skilled in the art, either from a gyroscope horizon determining device, an inertia frame, or a control post.

By means of a handle operated latch mechanism F_1 , the table F can be connected either with the pillar M whereby the table F cannot turn, or with the pivotable gun-carriage member B , whereby the table F can turn with the gun carriage in its gun traversing movement about its pivotal axis.

10 The double slide device operates to rotate the horizon adjustment shaft C through the lever G . The forks of this lever are trunnioned to an axially slidable coupling member G_1 in which the shaft C can turn and which co-operates with another coupling member slidable but non-rotatable on said shaft, and which is actuatable by a hand lever L , whereby the coupling member G_1 can be coupled to the shaft. The axis of the pin G_3 passes through the point of intersection of the carriage pivot axis and of the axis of the shaft C coinciding with the pivot axis which is at right angles to the shaft axis.

15 The cradle support D , the horizon adjustment telescope H , and the auxiliary sighting device J are so connected to the lever G and moved with the horizon adjustment shaft C that they are also simultaneously elevationally adjusted. These connections are made by links H , H_1 .

20 The sighting device J shown diagrammatically in the drawing contains a sighting line which is operated in known manner for elevation and transverse. Since the sighting device J always remains horizontal independent of all movements of the base, the direction connections calculated for the horizontal training circle and for the vertical elevation circle can be conveniently given in the sighting device without recalculation. By actuating the elevating and training mechanisms the sighting line will be kept directed on the target, in known manner, and the gun will be given constantly the correct line of fire.

25 The coupling mechanism which controls connection between the member G_1 and the horizon adjustment shaft C , also operates a coupling K_1 K_2 for engaging this shaft with a worm toothed sector K carried by the member K_1 of the coupling in which the shaft can turn, the other member K_2 being fastened to the shaft and slideable thereon by means of the hand lever L . The 30 sector K is engaged by a worm operated by a hand wheel as shown. When the coupling between the shaft C and the cradle support D is disengaged, the coupling K_1 K_2 is engaged, and rotation of the handwheel causes the shaft C to be turned and to cant the gun cradle trunnions about the axis of said shaft. By the aid of the horizon determining telescope H mounted on the shaft C and canting therewith to the same extent, it is possible to keep the gun trunnions 35 always horizontal even when the base A is tilted. For this purpose, by actuating the sector K by its worm gear, a hair line visible in the telescope H and which appears as horizontal when the base A is horizontal, can be kept coincident with the 40 always horizontal horizon. As the hair line is always parallel to the trunnion axis, horizontal location of the latter is thus assured. Elimination of base tilting in the plane of elevation, in this 45 case must be effected continuously by the elevating mechanism. To facilitate movement of

the parts about the axis of the shaft C the centre of gravity of these parts must be in said axes, and for this purpose there is provided a counter-weight N attached to the shaft C .

5 By means of the described mechanism the lever G , when the coupling member G_1 is engaged, can be maintained always vertical even when the base is unstable. For example, if the gun cants only transversely to the line of fire, then the slide F_5 is moved in the direction of canting and thus retains the lever G , and with it the attached parts including the gun, in their original direction in space. If the gun cants only in the plane of the line of fire then the slide F_3 receives such actuation that the lever G and parts connected thereto by links are compelled to rotate, relatively to the shift of the base, in the opposite direction to the carriage. If the gun cants in any direction, the movements of the slides F_3 and F_5 combine with each other in such a way that the lever G 10 remains vertical and the parts connected thereto retain their direction in space. If the carriage is turned, with the cross slides stationary, then the ball member G_2 turns in the slide F_5 without the latter having any reaction on the transmission of horizon adjustment movements by the lever G .

15 The double slide F may be operated by remote-control from a gyroscopic horizon fixed to the ship and for this purpose it can be coupled with the fixed base A . If the cross-slide F is connected with the pivotable gun carriage member B , then it can be controlled by an inertia device connected with the gun carriage or from a tri-axial control post.

20 This possibility of cross coupling the horizon-adjustment device (double slide or the like) either so that it is fixed to the ship, or is in pivotal relation thereto, can also be applied with advantage to gun carriages in which for constructional reasons, the horizon-adjustment device, as described above, is not situated so as to intersect the pivotal axis of the gun, but is arranged outside thereof. In this case, naturally, the horizon-adjustment device must first be fixed 25 to the ship by means of a device for imparting a counter-rotation thereto.

30 I claim:

35 A gun mounting for use on unstable platforms, ships, and the like, comprising a base fixed on the platform, a carriage member pivotable on said base about a vertical axis, means for supporting a gun including trunnions, a horizon adjustment shaft mounted in said carriage, connections between the shaft and said gun supporting means 40 for imparting canting movements to the axis of said trunnions by turning said shaft, a double slide movably mounted on said base, means engaging said slide for actuating the horizon adjustment shaft, said actuating means engaging said shaft at the intersection of the axis of the latter with the aforesaid vertical axis and said slide being subject to movements depending on the shifting of said base relatively to the horizon, means 45 for coupling the double slide with said base, means for coupling the double slide with said pivotable member, and means for selectively operating said coupling means to engage one of them while disengaging the other.
